Attorney.

UNITED STATES PATENT OFFICE

PHILIP H. EINBINDER, OF DENVER, COLORADO

COMBINED COAT AND VEST

Application filed February 18, 1930. Serial No. 429,289.

This invention relates to men's wearing apparel and has as an object the provision of an improved combined coat and vest wherein the vest is arranged as an integral or permanent part of the coat and adapted to be worn in embracing relation with the body of the wearer or folded back against the inner surface of the coat.

A further object of the invention is to provide an improved construction of combined coat and vest wherein the vest portion of a garment is formed as an integral part of, or fixed permanently to, a coat facing.

A further object of the invention is to provide an improved construction of combined coat and vest wherein the vest portion of the garment may be worn as such or folded within the coat portion without detracting from the fit of the garment.

A further object of the invention is to provide an improved construction of combined coat and vest adaptable to garments of varying styles.

A further object of the invention is to provide an improved combined coat and vest susceptible of tailoring by means of conventional methods.

My invention consists in the construction, arrangement and combination of elements hereinafter described, pointed out in my claims and illustrated by the accompanying drawings, in which—

Figure 1 is an elevation of a combined coat and vest embodying the features of my invention arranged as it would appear when worn as a combined garment. Figure 2 is a view of the garment shown in Figure 1 illustrating the manner in which the vest portion is folded away when the garment is to be worn as a coat only. Figure 3 is a view similar to Figure 2 illustrating a modified construction of the garment. Figure 4 is a view similar to Figure 2 illustrating the application of the invention to dress or tuxedo coats. Figure 5 is a cross section through one side of the garment shown in Figures 1 and 2 illustrating the vest portion in position to be secured in embracing relation about the body of a wearer. Figure 6 is a cross section similar to Figure 5 showing

the vest portion folded back within the coat proper.

In the construction of the combined garment as shown, a sack coat, designated generally by the numeral 10, is tailored in the usual and conventional manner with the exception of certain elements hereinafter described and is provided with the customary front flaps 11 extending from skirt to lapel and adapted to be marginally overlapped and buttoned together as is standard practice. In the conventional coat, the front flaps 11 are faced with material matching the coat and said facing material is turned outwardly adjacent the coat collar to form the finished lapels, the inner margin of said facing material being secured to edges of the coat lining 12. In the combined garment shown, the front flaps 11 are each provided with a facing 13, relatively somewhat wider than the facings of a conventional coat, the outer margins of said facings 13 being stitched to margins of the front flaps 11, as is usual practice, the bottom edges of said facings being secured to the bottom of the coat, top ends of said facings merging with the coat collar and the inner edges of said facings being free of the coat proper. The inner margins of the facings 13 are not cut straight, but have each an offset portion defining a flap 14 integral with said facing and having the form of one-half of a vest front, said flaps 14 having lower margins spaced upwardly from the lower ends of the facings 13 and upper margins tapered upwardly to merge into said facing 13 where the latter merges with the coat collar, so that, when the flaps 14 are smoothed back against the coat 10 and within said coat, the upper margins of said flaps pass below and clear the armholes of said coat, as is clearly shown in Figures 2 and 3. The coat lining 12 has an outer edge stitched to the inner edge of the facing 13 below the flap 14, as is usual, but said lining is formed with an integral flap 15 which corresponds with and is stitched along its margins to the edges of the flap 14, so that, when said flaps 14 are brought into embracing relation with the body of a wearer and buttoned or otherwise fastened together to form a vest, the lining 12 and lining flaps 15

15 are brought into embracing relation about the body of said wearer for a length equal to that of the vest portion and take whatever strains and distortions of fit may result from changes of position of the wearer, leaving the coat to hang freely, there being no connection between the lining 12 or lining flaps 15 and the facings 13 or flaps 14 between the lower and upper edges of said flaps 14 where they merge with said facings. As shown in Figures 5 and 6, buttons 16 are fixed on the inner sides and adjacent the inner margins of the flaps 14 and loops 17 are secured to the coat lining 12 in position to be engaged by said buttons 16 when said flaps 14 are folded within the coat 10 and hold said flaps smoothly within and against said coat, thus preventing unsightly bulkiness or wrinkling due to said flaps when the coat is worn without the vest flaps fastened together.

In the modification according to Figure 3, the construction is in all respects the same as above described, save that the flaps 14 are shown as stitched to inner margins of the facings 13 instead of being cut integrally therewith, this modification giving the same results as though said flaps were integral with said facings and permitting the use of contrasting material for the vest flaps, when desired, as well as permitting more economical cutting of material, in some instances.

In the modification shown in Figure 4, the improvement is shown as applied to a dress or tuxedo coat, in which case the vest flaps 14 have a different shape than those for a sack coat, but are otherwise the same in principle and function. It is of course obvious that the modifications of Figures 3 and 4 may be combined, when desired.

In practical use of the combined garment shown and described, the flaps 14 may be buttoned back within the coat 10 as shown in Figures 2, 3, 4 and 6 and the coat slipped on and worn as though there were no vest portion, said flaps 14 being folded back under the arms of the wearer and within the coat where they cause no discomfort or unsightly appearance. When a vest is desired, the buttons 16 are released from their loops 17 and the margins of the flaps 14 brought forward and together about the body of the wearer to be overlapped and buttoned together with the appearance of the conventional vest, the front flaps 11 of the coat being free to hang open, as shown in Figure 1, or to be buttoned together according to the wishes of the wearer. Thus the appearance and convenience of a vest may be had at any and all times without the necessity for a separate garment and at considerable saving in material and expense.

Since of necessity certain changes and modifications in the specific form and relation of the elements of my invention must be had in adapting the principle of the in-

vention to garments of varying styles and cuts, I wish to be understood as being limited solely by the scope of the appended claims, rather than by the illustrative showing and foregoing description.

I claim as my invention—

1. A combined coat and vest comprising a coat formed with front flaps, relatively wide facings on and secured along their forward margins to said front flaps, the rear margins of said facings being unsecured to said front flaps or coat, vest halves on and forming continuations of rear margins of said facings and a coat lining secured to margins of said vest halves and the otherwise free margins of said facings, said vest halves and the forward margins of said lining being entirely free of the body portion of said coat.

2. A combined coat and vest comprising a coat formed with front flaps, relatively wide facings on and secured along their forward margins to said front flaps, the rear margins of said facings being unsecured to said front flaps or coat, vest halves on and forming continuations of rear margins of said facings, means for positioning and holding said vest halves within and against inner surfaces of said coat and a coat lining secured to margins of said vest halves and the otherwise free margins of said facings, said vest halves and the forward margins of said lining being entirely free of the body portion of said coat.

Signed at Denver, in the county of Denver and State of Colorado, this sixteenth day of October, 1929.

PHILIP H. EINBINDER.
